US0D1106064S

(12) **United States Design Patent** (10) **Patent No.:** **US D1,106,064 S**
(45) **Date of Patent:** **** Dec. 16, 2025**

(54) **WIRELESS POWER BANK**

(71) Applicant: **Shenzhen Silicon Zhiyun Technology Co., Ltd.**, Guangdong (CN)

(72) Inventor: **Bin Zeng**, Guangdong (CN)

(73) Assignee: **Shenzhen Silicon Zhiyun Technology Co., Ltd.**, Shenzhen (CN)

(**) Term: **15 Years**

(21) Appl. No.: **29/998,691**

(22) Filed: **Apr. 15, 2025**

(30) **Foreign Application Priority Data**

Apr. 3, 2025 (CN) 202530174779.8

(51) **LOC (15) Cl.** **13-03**

(52) **U.S. Cl.**

USPC **D13/108**

(58) **Field of Classification Search**

USPC 13/103, 107, 108, 118, 119; 14/434

CPC H02J 7/0044; H02J 7/342; H02J 50/10

(57) **CLAIM**

The ornamental design for a wireless power bank, as shown and described.

DESCRIPTION

FIG. 1 is a perspective view of a wireless power bank showing my new design;

FIG. 2 is another perspective view thereof;

FIG. 3 is a front elevation view thereof;

FIG. 4 is a back elevation view thereof;

FIG. 5 is a left side elevation view thereof;

FIG. 6 is a right side elevation view thereof;

FIG. 7 is a top plan view thereof;

FIG. 8 is a bottom plan view thereof; and,

FIG. 9 is a perspective view of the wireless power bank in an open position.
The broken lines depict portions of the wireless power bank that form no part of the claimed design.
